UNITED STATES PATENT OFFICE.

GEORGE M. O. JENKINS, OF LONDON, ENGLAND, ASSIGNOR TO WESTERN ELECTRIC COMPANY, INCORPORATED, OF NEW YORK, N. Y., A CORPORATION OF NEW YORK.

PNEUMATIC VALVE.

Application filed October 23, 1924, Serial No. 745,382, and in Great Britain April 23, 1924.

This invention relates to receiving valves and particularly to such valves as are used in connection with pneumatic conveying systems.

5 The principal object of this invention is to provide a valve for receiving tickets or cards at each of the selective terminals of pneumatic conveying systems of the character such as are commonly used in telephone exchanges for handling toll tickets.

Heretofore, the valves which have been employed in pneumatic conveying systems have been of the manually operated or of the complicated and expensive automatic 15 discharge roll type. This invention provides a simple air-tight automatic pneumatic valve which operates instantaneously to discharge received tickets and thereupon immediately automatically restores itself 20 until the next ticket registers. The valve of this invention comprises a compartment, in which, a vacuum is normally maintained, provided with means, actuated by the presence of a ticket therein, for effecting the cut-

25 ting off of the vacuum from the compartment and for effecting or permitting the release of the ticket therefrom. The aforementioned means provided in the compartment consists of a hinged door of wire gauze 30 against which the ticket to be collected is drawn by suction, the door then operating to cause an electromagnetic device, such as a plunger magnet, to effect the closing of a valve controlling the vacuum and opening 35 the compartment to release the ticket.

The invention will be more readily understood from the following description of a preferred embodiment which is illustrated in the accompanying drawing in which:

40 Fig. 1 is a front view of the valve of my invention shown in partial section;

Fig. 2 is a sectional side elevation taken along the line 2—2 of Fig. 1;

Fig. 3 is a side elevation of the electro- 45 magnet and release mechanism; and

Fig. 4 is a view of the ticket releasing mechanism.

Referring to the drawing in which like characters designate like parts in the several views, numeral 1 indicates the casing of 50 the valve which is rectangular in shape and may be of any suitable material such as brass, having a mounting plate 2, by means of which the valve is attached to the tube 55 in any desired manner. Extending down

the center of the interior of the casing is a partition 3 which divides the valve casing into two compartments, 4 and 5, which are connected together at the base of the valve beneath the lower edge of partition 3. An 60 air tight glass observation window 6 is provided in the front face of casing 1.

A member 7 completely closes the upper end of the compartment 4 except for a passage 8 in which a leaf valve 9 is positioned. 65 Leaf valve 9 is rigidly fastened to the rod 10 which is journaled to the casing 1 and is frictionally adjustable by means of the collar 11 and lock screw 12 in the exterior of casing 1. This valve regulates the size of 70 the opening in the passage 8. The upper surface of member 7 is connected in any manner well known in the art to a vacuum pump which operates continuously, whereby air is sucked downward through the right 75 hand compartment 5, through the opening beneath the partition 3, and thence upward through compartment 4 and passage 8 to the pump.

A thin flexible leaf spring 13 is secured 80 at its center by means of tap screws to a cleat 14 across the lower end of passage 8. Suspended from each end of spring 13 is a thin chain 15 connected at its lower extremity to each end of a trap door 16 which 85 is pivotally mounted along its longitudinal center line on the rod 17 journaled in the walls of the casing 1, with one end extending through one side a short distance, as shown in Fig. 1. The closure surfaces of door 16 90 are provided with thin layers 18 of leather or like material in order to insure an air-tight joint when in closed position.

The rectangular flap door 19 of wire 95 gauze extends across the opening beneath partition 3, its upper edge rigidly fixed upon a pivotal rod 20 which is journaled in the walls of casing 1 with one end extending through and shaped like a crank to form the ticket operating member 21, the bearing 100 end of which 22 is of insulating material. The contact springs 23 and 24 mounted on the side wall of casing 1 and insulated therefrom and from each other in the usual manner, are operated by contact 22 which 105 engages spring 23 as the flap door 19 and its crank rod 20 are actuated.

Rigidly secured to the right-hand side of the casing 1, is a plunger solenoid 25 provided with a suitable number of turns, the 110

core of which 26, having a longitudinal slotted extension 27 which carries a coiled spring 28 attached at its lower end to the adjustable shackle 29 on the bracket 30 which is mounted in an extension 31 of the right-hand side of the casing. As before mentioned, extension 27 is slotted longitudinally and in the slot is located a link, also provided with a longitudinal slot, through which and also through member 27 passes a screw pin 33, upon which link 32 rides and which also limits its motion. Link 32 which is rigidly fastened to rod 17 by means of a tap screw, carries a contact operating member 34, the bearing point 35 of which is of insulating material adapted to engage spring 36 which normally makes contact with spring 37. Springs 23 and 24, controlled by the rod 20 secured to the gauze door 19, are arranged in the circuit of a slow acting relay which energizes when the contacts are closed and close the circuit of the solenoid 25 in which circuit are located the normally closed springs 36 and 37.

25 Compartment 5 is connected by a tube of suitable size to an operator's position where the tube is provided with a slot in which the toll ticket is inserted, the ticket having been previously folded as indicated by numeral 38 of Figs. 2 and 4, with the fold uppermost.

The operation of the apparatus may be described as follows: as before mentioned, member 7 is connected to a vacuum pump so that air is continuously drawn down into compartment 5 and up out of compartment 4 through the gauze door 19 and past valve 9 as indicated by the arrows in Fig. 2. Valve 9 is adjustable to govern the suction of a suitable vacuum for operation. When a ticket is to be collected, it is inserted in the tube as heretofore described, is drawn into compartment 5 and against the gauze flap door 19 to which it clings as shown in Fig. 4. Consequently the ticket, closing off the suction through the gauze door 19, causes the air pressure behind it to close the door which rotates rod 20 and actuates 21 to close contact springs 23 and 24 which closes the circuit to operate a slow acting relay not shown. This relay, upon operating, closes the circuit of the solenoid 25, which, upon energizing, pulls up the core 26 and with it the core extension 27, thereby rotating link 32 which is rigidly mounted upon rod 17 on which the trap door 16 pivots, so that the right-hand half of the door drops downwardly and the other half, to which the chains 15 are attached, moves upwardly. 60 The chains 15, being loosened, release the tension of leaf spring 13 which immediately snaps upwardly to close passage 8, the vac-

uum in the apparatus ceases, and the ticket which, under vacuum, clung to the gauze door now slips off this door and passes through the open door 16 into any suitable receptacle and is collected. The release of the ticket by gravity is aided somewhat by the continued downward movement of air in the compartment 5 after the vacuum has been cut off.

The action of the link 32 which, with its contact operating extension 34, having opened the normally closed contacts 36 and 37, has accordingly opened the solenoid circuit 25 which, upon the deenergizing of the slow acting relay permits the apparatus to return to normal, the slow acting relay insuring that the door is opened for a sufficient interval to allow the ticket to pass therethrough.

While this specification describes a preferred embodiment of this invention, it will be understood that changes may be made in form, construction and proportion without departing from the spirit of this invention, within the scope of the appended claims.

What is claimed is:

1. In combination, a receiving valve comprising a compartment, a door therefor, a hinged member therein, means for normally maintaining a vacuum therein, said vacuum causing a ticket to be drawn against said hinged member to move the same and a valve operated thereby for shutting off the vacuum, and means simultaneously operated by said hinged member to open said door to release the ticket.

2. A receiving valve according to claim 1 in which said hinged member closes the circuit of an electromagnet which opens said door, said door being mechanically connected to the valve which shuts off the vacuum.

3. A ticket receiving valve comprising a compartment, means for normally maintaining a vacuum therein, a hinged door for said compartment against which the ticket is drawn by suction, magnetic means actuated by said door to shut off the vacuum, release said ticket and return said valve to normal.

4. An automatic valve for pneumatic systems comprising a vessel divided into two compartments, means for normally maintaining the vacuum therein, a hinged member provided in one compartment against which a ticket is drawn, an electromagnetic device, and a door normally closing the compartment in which the ticket is present, said door being actuated by said device for shutting off the vacuum and releasing said ticket.

In witness whereof, I hereunto subscribe my name this tenth day of October A. D., 1924.

GEORGE M. O. JENKINS.
